H. W. FLETCHER

EARTH BORING DRILL

Filed Sept. 13, 1920

Fig. 1

H. W. FLETCHER - INVENTOR.

BY *Jesse R. Stone*
ATTORNEYS.

UNITED STATES PATENT OFFICE.

HAROLD W. FLETCHER, OF HOUSTON, TEXAS, ASSIGNOR TO HUGHES TOOL COMPANY,
OF HOUSTON, TEXAS, A CORPORATION OF TEXAS.

EARTH-BORING DRILL.

Application filed September 18, 1920. Serial No. 410,035.

To all whom it may concern:

Be it known that I, HAROLD W. FLETCHER, a citizen of the United States, residing at Houston, Harris County, Texas, have invented a certain new and useful Improvement 5 in Earth-Boring Drills, of which the following is a full, clear, and exact description, such as will enable others skilled in the art to which it appertains to make and use the same.

My invention relates to an improvement in rotary earth boring drills and has particular application to roller drills adapted to cut in hard formation, such as rock, hard 15 sand, etc., in the drilling of wells for oil, water, gas, etc.

In the drilling of such wells, it is customary to cut the strata, through which the drill progresses, by the rolling of toothed cutters 20 on the bottom of the hole, thus disintegrating the material, which is ground up and is carried upwardly away from the cutters in suspension by streams of flushing fluid pumped downwardly through the drill stem.

The flushing fluid ordinarily used is water 25 carrying large quantities of mud in suspension. This mud naturally contains quantities of sand and grit, and, in its passage downwardly through the channel in the head of the bit, so as to discharge upon the cutters, acts to wear away the walls of the channel. Furthermore, in drills of this 30 character, where the head of the bit is longitudinally divided, it has been customary to form the water channels by the cutting of 35 grooves in the meeting faces of the separate parts of the head. In this construction, unless the parts of said head fit very tightly together, flushing fluid may escape laterally, in small quantities, from the channel 40 to the outside of the head. These small passages naturally are worn and it soon happens that a material leakage occurs from the channel laterally along the meeting faces of 45 the split head.

An object of my invention is to provide a drill of the character set forth, having a removable water course therethrough, which, when worn, may be replaced.

Another object is to so form the channel

for the flushing fluid that there will be no lateral escape for the fluid, as in the previous types of split head bits.

Another object is to provide a drill having reaming rollers in the sides of the head, 55 these rollers being set in a diametrical recess through said head and a channel for the flushing fluid, which will conduct the fluid downwardly through said recess and discharge the same upon the lower cutters in 60 the usual manner.

Another object is to provide a means of conducting lubricant through the longitudinally divided head and the central recess therein so as to allow no escape for the 65 lubricant.

I have shown in the drawing a preferred embodiment of my invention, Fig. 1 being a central longitudinal section through the same on the line 1—1 of Fig. 2; and Fig. 2 70 being a transverse section on the line 2—2 of Fig. 1. Like numerals of reference are applied to like parts in both the views.

The type of drill disclosed in the drawing is similar to that disclosed in the prior 75 patent to Hughes, No. 1,174,575, issued March 7, 1916, and comprises a head 1 approximately cylindrical in shape and having a reduced upper shank 2, threaded for attachment to a drill stem 3. At the extreme 80 upper end the head is still further reduced in diameter at 4 and threaded for attachment to a collar 5, having an upper nipple 6 for attachment to a lubricant container 7.

The head 1 is formed with a V-shaped 85 slot 8 in the forward end thereof, on the flat faces of which are provided threaded stub shafts 9, upon which the bearings 10 of rotary frusto-conical cutters 11 are removably mounted. The head is longitudinally divided into two parts along a central 90 plane 12. These parts are maintained in registered position by means of transverse locking bolts 13, held against removal by means of cotter pins 14, and also by the 95 threading of the upper shank 2, within the drill stem 3. Lubricant is conducted to the bearings from the container 7, through a central duct or channel 14 in the nipple 6, and branching ducts 15 leading from said 100

central channel downwardly through the collar 5, to an annular groove or recess 16 in the base of said collar, from which the lubricant is fed downwardly in an inclined 5 direction through oil ducts 17, through a central recess 18, and from thence in an outwardly inclined direction to discharge the lubricant through connecting ducts 19 in the cutter shafts 9, from which the lubricant is fed to the bearings 10, as shown.

Reaming rollers 20 are mounted in housings or pockets 21, formed by recesses cut in the contacting faces of the longitudinally divided head. These pockets are formed opposite each other and are connected by a diametrical opening or recess 18 through the head. This connecting opening 18 is formed in the head for purposes of construction, it being practically impossible in casting steel 20 for the head to form a web between the opposite pockets 21 and also allow for a central water channel, to be later described. The reaming rollers 20 are mounted upon upright pins 22, set in the meeting faces of 25 the head above and below the pockets 21. The upper and lower ends of the pins 22 are set in squared recesses 23 to prevent rotation of the pins, in an obvious manner. The flushing fluid is conducted downwardly 30 through the head by means of a central removable water course 24, formed by means of a length of pipe or tubing 25 threaded at 26, at the upper end, for attachment to the collar 5. A plurality of inwardly inclined 35 channels 27 allow entrance of the flushing water from within the drill stem to the upper end of the water course 25. This water course is mounted in central registering grooves in the meeting faces of the two parts 40 of the head. Flushing fluid passing downwardly through this water course is discharged upon the upper edges of the cutters 11 and is adapted to clean the same of material adhering thereto and to wash the cuttings upwardly outside of the drill stem to 45 the surface.

The advantages of a central removable water course, such as disclosed herein, are particularly in the fact that it is removable 50 when worn and allows no lateral escape of the fluid from the head of the bit. It allows water to be discharged through the central passage or opening 18 connecting the reamer pockets without the liability of the dispersing of flushing fluid laterally against the reaming rollers.

The forming of removable lubricant ducts 17, which are driven downwardly through the head of the bit to a point well beyond the central opening 18, provides a continuous oil duct from which no lubricant can escape, and the channels may be readily bored in the head in an economical manner.

Having thus described my invention, what

I claim as new and desire to protect by Letters Patent is:

1. In a rotary earth boring drill, the combination of a longitudinally divided head, cutters on the forward end thereof, reaming rollers mounted in a recess extending diametrically through said head, a removable water course mounted in grooves in the meeting faces of said divided head and extending longitudinally through said recess, and a collar at the upper end of said head having channels connecting with said removable water course.

2. In a rotary earth boring drill, the combination of a longitudinally divided head, cutters on the forward end thereof, reaming rollers mounted in a recess extending diametrically through said head, and a removable water course mounted in grooves in the meeting faces of said head and extending longitudinally through the said recess and said head in the manner described.

3. In a rotary earth boring drill, the combination of a longitudinally divided head, rolling cutters on the forward end thereof, a removable water course mounted in grooves in the meeting faces of said head, a collar at the upper end of said head having channels connecting with said removable water course and a lubricator on said collar having lubricant ducts leading to an annular groove in the base thereof and tubes leading from said groove through said head to said cutters.

4. In a rotary earth boring drill, the combination of a head longitudinally divided into a plurality of parts, registering grooves in the contacting faces of said head, and a removable pipe extending longitudinally through said head and fitting with said grooves, and a collar constituting a lubricator attachment at the upper end of said head having channels for flushing fluid therein connecting with said central pipe above said head, in the manner described, said collar acting also to assist in holding the parts of the head together.

5. In a rotary earth boring drill, the combination of a head, cutters on the forward end of said head, reaming rollers mounted in pockets in the sides of said head, said 115 pockets being connected by a central opening and a central removable pipe extending downwardly through said head and adapted to conduct the flushing water through said opening and discharge the same at the forward end of the bit.

6. In a rotary earth boring drill, a longitudinally divided head, cutters on the forward end thereof, an enlarged passage in said head, a removable water-course mounted in the meeting faces of said head and making a close fit therewith only at the upper and lower ends of said head and adapted

to convey flushing fluid through said head and said enlarged passage in the manner described.

7. In a rotary earth boring drill, a head, 5 rotary cutters thereon, said head having a diametrical pocket therethrough, a lubricant container on said head and removable ducts extending from said lubricator longitudi-

nally through said head and said pocket to conduct lubricant to the bearings of said 10 cutters.

In testimony whereof, I hereunto affix my signature, this the 8th day of September, A. D. 1920.

HAROLD W. FLETCHER.
